REMOVAL OF CARBONACEOUS MATERIALS
FROM VESSELSLyman C. Huff, Chicago, Ill., assignor to Universal
Oil Products Company, Chicago, Ill., a corpora-
tion of South Dakota

Application January 26, 1931, Serial No. 511,196

5 Claims. (Cl. 196—69)

This invention relates to the removal of carbonaceous materials from vessels generally, and is more particularly directed to a method and means for removing deposits of coke, carbon, or other carbonaceous materials or residues remaining within reaction chambers, coke stills, residuum redistilling chambers or the like employed in an oil cracking operation.

There is disclosed in United States Patent No. 10 1,548,004 an apparatus for removing carbon deposited in an enlarged reaction chamber, consisting of a flexible metal member releasably supported within said reaction chamber at a plurality of different vertical points and adapted to be 15 distributed vertically throughout the deposited carbon collected in said chamber and to be withdrawn therefrom to disrupt the entire mass of carbon deposit. The present invention constitutes specific improvements in the method and means 20 of removing carbon deposits, as disclosed in my said United States Patent No. 1,548,004.

In one particular embodiment, the present invention comprises a method and means of removing coke or carbonaceous material which may 25 be deposited within an enlarged chamber used in any well-known type of oil cracking process. While the following description will deal with the application of the invention to a reaction chamber of a cracking process, it is to be understood 30 that the invention is not to be limited thereby, reference to such a particular chamber being merely for purposes of illustration only. The principles of the invention are applicable to any type of apparatus which may be employed in such 35 cracking processes and wherein carbonaceous accumulations may occur.

A feature of my invention provides for the withdrawal of a cable, suspended in the carbon deposited within a chamber, through a lower man- 40 way opening, and the use of a series of roller blocks or sheave wheels to guide said cable during its removal from said chamber, and to change the direction of pull from a substantially vertical plane to a substantially horizontal plane.

45 Another feature of the invention provides for attaching or anchoring one end of a cable to the bottom of a manway cover so that on removal of said cover, a free end of said cable will be available for withdrawal, thus affording an easy 50 access for the pulling of the balance of the cable.

55 My invention may further provide for disposing a cable in a series of substantially horizontal planes vertically disposed throughout a chamber, or through that portion of the chamber wherein

carbonaceous materials may settle. The cable may be wound in a spiral form in each of said planes, starting at a point near the center of the chamber and continuing to a point near the inner wall of said chamber.

60 Another feature provides for a variation in the horizontal spacing between the turns of a coil or a number of coils, and any other coil or coils disposed at different elevations in a chamber. For example, the spacing between the turns in 65 the three lowest coils within a chamber may be closer than the spacing between the turns in the higher coils. The vertical spacing between the various substantially horizontal coils may also be varied to suit requirements.

70 Another feature of my invention permits pulling the cable from a starting point near the center of each coil, which point will be at substantially a vertical mid-point of the chamber, and extending out toward the inner wall of said 75 chamber. This may be accomplished by winding a cable in each layer or coil, starting always at a central point, continuing out to the outer turn of each coil, and then extending back from the outer turn to the central point of the next 80 succeeding higher coil, and so on throughout the entire series of coils within the chamber.

75 My invention also provides for winding each coil in a direction opposite to the winding of the next preceding coil. For example, the first coil 85 may be wound in a clockwise direction; the next highest coil in a counter-clockwise direction; the third or next higher coil again in a clockwise direction, and so on throughout all of the succeeding coils to be placed within the chamber.

90 Other and further objects and advantages of the invention will be apparent from the following description and accompanying diagrammatic drawings showing one form of application of the invention, and wherein,—

95 Fig. 1 is a vertical cross-section of a chamber, showing a cable disposed therein in one applied form of the invention;

Fig. 2 is a horizontal section of a chamber, taken on a line C'—C' of Fig. 1;

Fig. 3 is a horizontal section of a chamber, taken on a line D'—D' of Fig. 1; and

Fig. 4 is a fragmentary sectional view, similar to Fig. 1, showing a chamber charged with carbonaceous materials and accessory means for 105 the removal of a cable and such carbonaceous materials.

110 Referring to the drawings, there is shown an enlarged vertical reaction chamber 1, of any conventional type, having an upper manway or open-

ing 2 and a lower manway or opening 3, the latter having a suitable removable cover 4. Suitably welded or otherwise secured to the inner surfaces of said chamber 1 are a series of lugs 5, adapted to receive and retain supporting members or wires 6. The lugs 5 may be fastened or secured at various points around the entire circumference of chamber 1 in substantially horizontal planes, spaced at various elevations, corresponding substantially to the planes in which the coils of a cable or other flexible metallic member 7 may be disposed. Wires or supports 6 may be strung between each pair of diametrically opposed lugs 5 to form a series of radial supports upon which the cable 7 may be coiled. Said wires or supports are of sufficiently heavy gauge as to support the normal weight of any cable or metallic member employed, yet are of sufficiently light gauge to permit their breaking away from lugs 5 when the cable 7 may be pulled from the chamber 1. Cable 7 is employed to disrupt the coke or other deposition within chamber 1, and may be disposed at the various substantially horizontal planes vertically disposed throughout said chamber in which the cable is wound, as indicated diagrammatically in the drawings at A, B, C, D, E, F, G, H, I, J, K, L, M, and N.

The lower end of cable 7 may be wound in the form of a small coil 8, and the extreme end of said cable, below the coil 8, may be fastened by any desired means to the manway cover 4 at a point 9. If desired, said cable may be welded or otherwise permanently secured to manway cover 4, but may preferably be clamped or otherwise attached to said cover in such manner as to be readily removable therefrom on removal of the cover from said chamber. This will permit a hitch being readily made to the lower end of the cable so that it may be wound around a drum of a winch or other suitable cable-pulling device (not shown). The cable, of course, may be ejected from the chamber by means of any other suitable device, such as a tractor, in which case, if cover 4 should be permanently attached to the end of the cable, no serious difficulties would be presented. Coil 8 may preferably be wound within the neck of manway opening 3, so that when the cable is placed within the chamber, coil 8 will lie relatively close to cover 4 so as to be easily pulled free from the coke deposition within the chamber when such cover is removed for the cleaning of the chamber; thus affording a sufficient length of cable to form a hitch below the bottom of a chamber.

It frequently happens that the carbonaceous deposit near the bottom of a chamber may be of a relatively tougher nature than that in the upper portions thereof, due, in part, no doubt, to its being subjected to a greater time period of reaction. In order that the strain imposed on a cable during the pulling operation may be equalized throughout the entire length of said cable, the horizontal spacing between the turns of the cable and the vertical spacing between adjacent coils thereof may be less in the lower portion of said chamber, (or any other portion where the coke is known to be consistently harder or tougher) than in the remaining portion of said chamber. It will be noticed particularly in Fig. 1, for example, that the horizontal spacing S between each of the turns in the three lowest coils in the chamber is less than the spacing S' between each of the turns of the coils in the upper portion thereof; and also that the vertical spacing V between the first and second and the second and third coils is less than

the vertical spacing V' between any two adjacent higher coils.

It will be noted, on reference to Figs. 1, 2 and 3, that each coil of cable 7 may be wound from a central starting point, such as P' or P, from which point it may be spiralled or coiled in a substantially horizontal plane to an outer point closely approximating the wall of chamber 1, such as Q or Q'; thence from said latter points, back to the central points P or P' of the next succeeding coil. By effecting a winding of the cable in this manner, provision is made for first dislodging the carbonaceous material from the center of each successive layer throughout the chamber, forming a clear path in each successive layer for the removal of deposits loosened by the continued pulling of the cable lying from said central point to the outer limits of the interior of the chamber. In this manner, all coke may fall in the most direct path to the bottom of manway 3 and out of the chamber. Another advantage for commencing each coil of cable at or near the center of the chamber is that a means is provided whereby the removal of each successive layer of coke is started when the cable is in a substantially vertical plane, imposing less strain on the cable than when the pull is exerted in an inclined plane. In this manner, there is maintained a uniform strain on the cable throughout its entire length during the entire pulling operation.

It will be noted, particularly in Fig. 2, that the cable may be coiled in a counter-clockwise direction, and that such counter-clockwise winding may be utilized for the coils disposed in the planes A, E, G, I, K, and M, as well as in the plane C in Fig. 1; while in Fig. 3 the cable is coiled in a clockwise direction which may also be utilized for the coils disposed in the planes B, F, H, J, L, and N, as well as in plane D of Fig. 1. Thus it will be apparent that each coil may be wound in the opposite direction to the next preceding coil. It has been found that this arrangement permits the cable, while being removed from the chamber, to coil in such a manner that it does not become snarled or tangled, thereby greatly facilitating replacement of the cable in the chamber after the cleaning operation has been completed.

Referring particularly to Fig. 4, there is shown a lower portion 1 of a chamber, with a lower manway 3 and lugs 5 from which wires or supports 6 may be suspended and on which cable 7 may be disposed. Communicating with the outlet or manway 3 and over which cable 7 may pass on discharge from said chamber, are sheave wheels 8 arranged in series and so disposed that the cable passing over the grooves of said wheels will conform to a relatively large radius, thus minimizing any tendency of the strands of said cable to stretch or break. This series of rollers or sheave wheels 8 may serve to change the direction of pull on the cable from a substantially vertical to a substantially horizontal plane, so that the cable may be wound around the drum of a winch or other suitable pulling device placed at or near the ground level and out of the way of the falling coke being discharged from the chamber. The deposit of coke 9 within said chamber, on a pulling of said cable and a resulting loosening, falls by gravity onto a conveying device 10, such as a continuous belt conveyor, passing the disrupted coke 11 to storage, to a coke car, or elsewhere, as desired.

From the foregoing, it will be apparent that I have devised a novel method and means for the removal of a deposit of coke, carbon, or carbonaceous material from vessels employed in oil crack-

- ing processes by pulling from such deposit a flexible metallic member suspended within said vessel and carbonaceous material, disrupting said deposit and permitting the removal thereof from 5 said vessel by gravity. Briefly, provision may be made for the pulling of a flexible metallic member through the lower manway opening of a vessel being cleaned; changing the direction of pull on such member by means of a series of 10 roller blocks, sheave wheels or the like in order that said flexible member may be bent to conform to a sufficiently large radius to prevent undue stress to said member; anchoring one end of said flexible member to the cover plate of the 15 bottom manway opening of a vessel to permit easy accessibility to said member; placing the flexible member in a vessel in the form of a series of substantially flat, spiral coils, extending horizontally from substantially the central point of 20 said vessel to a point near the inner wall thereof, and disposing each of said coils at superimposed levels within a vertical vessel; disposing the turns of the coils of said flexible member in such manner that the horizontal spacing between such 25 turns and the vertical spacing between adjacent coils in superimposed relation within any desired portion or portions of a vessel in closer relation than the vertical and horizontal spacings of said coils in other portions of said vessel; winding 30 each successive coil of said flexible member so that the pulling of each coil is commenced at its central point, said pulling continuing progressively throughout said coil to its outermost point and thence returned to the central portion of the 35 next succeeding coil; and winding or spiralling each of said superimposed coils in alternate opposite directions.
- It is to be understood, of course, that any one, any combination, or all of the features of the 40 invention may be utilized to facilitate cleaning or the removal of deposited material from any type of apparatus or equipment to which the features of the invention may relate or apply.
- I claim as my invention:—
- 45 1. A process for the removal of carbonaceous deposits from vessels employed in oil cracking processes which comprises disposing a flexible metallic member within a vessel employed in a cracking operation in a plurality of substantially horizontal superposed spirals, prior to the commencement of said operation, alternate spirals of said member being wound in opposite directions outwardly from the center, and disrupting and removing the mass of carbonaceous deposit 50 formed within said vessel during said cracking operation by forcibly withdrawing said flexible metallic member from said vessel on discontinuance of said cracking operation.
- 55 2. A process for the removal of carbonaceous deposits from vessels employed in oil cracking processes which comprises disposing a flexible metallic member, prior to the commencement of a cracking operation, in superposed horizontal planes within said vessel, said member being wound in spirals in each of said planes from an 60 80
- axis common to each of said spirals, the lowermost spirals of said flexible member being spaced in closer superposed relation than the uppermost spirals of said member, and disrupting and removing the mass of carbonaceous deposit formed within said vessel during said cracking operation by forcibly withdrawing said flexible metallic member from said vessel on discontinuance of said cracking operation. 85
3. A process for the removal of carbonaceous deposits from vessels employed in oil cracking processes which comprises disposing a flexible metallic member within a vessel prior to the commencement of a cracking operation wound in spirals, each of said spirals being successively superposed in spaced horizontal planes within said vessel and wound from an axis common to all of said planes in a direction alternate and opposite to the direction of winding of the preceding or succeeding spiral, and disrupting and removing the mass of carbonaceous deposits formed within said vessel during the cracking operation by forcibly withdrawing said flexible metallic member from said vessel on discontinuance of said cracking operation. 90
4. A process for the removal of carbonaceous deposits from vessels employed in oil cracking processes which comprises disposing a flexible metallic member within a vessel employed in an oil cracking operation in a plurality of substantially horizontal superposed spirals, the successive or adjacent windings of said superposed spirals disposed in the lower portion of said vessel being spaced in relatively closer relation to each other than the successive windings of spirals disposed in the upper portion of said vessel, and disrupting and removing the mass of carbonaceous deposit formed within said vessel during said cracking operation by forcibly withdrawing the imbedded flexible metallic member from said vessel on discontinuance of the cracking operation. 100
5. A process for the removal of carbonaceous deposits from vessels employed in oil cracking processes which comprises disposing a flexible metallic member within a vessel prior to the commencement of an oil cracking operation, in a plurality of superposed horizontal planes spiralled to conform to successive layers of carbonaceous deposit to be formed during the continuance of such cracking operation, alternate spirals of said member being wound in opposite directions outwardly from the center, and disrupting the successive layers of the accumulated carbonaceous deposit surrounding said flexible member within said vessel on discontinuance of said cracking operation by withdrawing said flexible member at a point commencing substantially at the central portion of the initial layer of said accumulated deposit, continuing such withdrawal and disruption throughout the remainder of said layer, and repeating the disrupting and withdrawing action throughout the remaining successive layers of said accumulated deposit. 110
